UNITED STATES PATENT OFFICE.

JOSEPH C. MOSLEY, OF ST. LOUIS, MISSOURI.

ELECTRICALLY-OPERATED LOCK.

1,114,628,

Specification of Letters Patent.

Patented Oct. 20, 1914.

Application filed September 12, 1913. Serial No. 789,490.

To all whom it may concern:

Be it known that I, JOSEPH C. MOSLEY, a citizen of the United States, residing in the city of St. Louis and State of Missouri, have invented new and useful Improvements in Electrically-Operated Locks, of which the following is a specification.

This invention relates to improvements in electrically operated locks and has particular application to a coin controlled lock of this type.

In carrying out the present invention, it is my purpose to provide a lock of the class described which will be key controlled and constructed in such manner that the key cannot be removed from the lock until after a coin has been deposited therein and the locking bolt actuated to locking position.

It is also my purpose to provide a lock of the type set forth which will be constructed in such manner that should the locking bolt fail to work for any reason, the coin deposited may be recovered by the user.

Furthermore, I aim to provide an electrically operated coin controlled lock wherein the coin will be automatically thrown out of active position as the bolt moves to locking position and wherein the bolt, after assuming locking position, will be relieved of the influence of the electro responsive device and placed under the control of the key of the lock so that the bolt may be retracted by the key.

A further object of the invention is the provision of a lock of this character wherein the key will be locked against removal as the latter is manipulated to retract the bolt, thereby preventing removal of the key from the lock when the latter is inactive.

With the above and other objects in view, the invention consists in the construction, combination and arrangement of parts hereinafter set forth in and falling within the scope of the claims.

In the accompanying drawings; Figure 1 is a view in elevation of a locker equipped with a coin controlled electrically operated lock constructed in accordance with the present invention. Fig. 2 is a vertical sectional view through the casing of the lock, the mechanism of the lock being shown in elevation. Fig. 3 is an enlarged fragmentary sectional view on the line 3—3 of Fig. 2. Fig. 4 is a fragmentary sectional view on the line 4—4 of Fig. 2. Fig. 5 is a sectional view on the line 5—5 of Fig. 2; Fig. 6 is a longi-

tudinal sectional view through the lock casing showing a modified form of mechanism. Fig. 7 is a fragmentary sectional view through the coin chute.

Referring now to the accompanying drawings in detail, the numeral 1 designates the casing of a lock, which casing may be constructed of any suitable or desired material and of any desired outline. Slidably mounted within guides within the casing and adapted to be projected outwardly of one end wall of the casing is a locking bolt 2 having formed on its under surface a depending lug 3 and equipped at its inner end with an upstanding arm 4 carrying an armature 5 disposed within the influence of an electromagnet 6. Leading into the top of the casing adjacent to the end thereof opposite that through which the bolt is adapted to be projected is a coin chute 7 arranged at an angle to the vertical and having the lower end thereof equipped interiorly with contacts 8, 8 suitably spaced apart and connected in series in an electric circuit with the magnet 6. By means of this construction, it will be seen that when a coin is deposited in the chute 7 such coin will bridge the contacts 8, 8 and so close the circuit of the magnet 6 whereby the latter will be energized and act upon the armature 5 with the effect to slide the locking bolt 2 to projected or locking position.

Immediately succeeding the movement of the locking bolt to locking position, the coin bridging the contacts 8, 8 is removed and this is accomplished, in the present instance, through the medium of a horizontal bar 9 secured to the upper end of the arm 4 and disposed in a plane parallel with that of the locking bolt and having the free end thereof cut out as at 10 and working through a slot formed in the front wall of the coin chute 7 immediately adjacent to the lower end thereof. When the bolt is retracted, as illustrated in Fig. 2, the cut out portion 10 of the bar 9 forms in effect a continuation of the channel in the coin chute 7 and as the bar 9 is moved with the locking bolt, under the action of the magnet 6, the wall of the cut away portion 10 carries the coin out of engagement with the contacts 8, 8. A vertical chute 11 leads out of the lower edge of the casing 1 and is disposed in a plane to one side of the coin chute 7 and adapted to receive the coin as the latter is moved off of the contacts 8, 8 under the action of the cut away portion of the arm 9. Thus, as

the locking bolt is moved to locking position, the coin is removed from the contacts 8, 8 and permitted to drop into the chute 11 whereby the circuit through the magnet 6 is broken and the latter deenergized so that the locking bolt is relieved of the influence of the magnet. The lower end of this chute 11 may communicate with a suitable coin receptacle as is obvious. Formed in the front wall of the lock casing 1 at a point below the locking bolt 2 and in proximity to the lug 3 is a key hole 12, while suitably connected to the locking bolt at a point in advance of the lug 3 and depending therefrom is a right angled arm 13 having the horizontal limb thereof extended rearwardly and forked or bifurcated as at 14. 15 designates the shank of a key, carrying adjacent to its inner end, a wing 16 adapted to be passed through the key hole 12 and swung into engagement with the lug 3, when the bolt is in locking position, whereby such bolt may be retracted. The outer end of the shank 15 is equipped with a manipulating head 17 and formed adjacent to such head with a groove 18 and as the bolt is retracted the forked end 14 of the horizontal limb of the right angled arm rides into engagement with the groove 18 in the key shank and so eliminates the possibility of removing the bolt from the lock after the key has been retracted.

In order that a coin deposited within the coin chute 7 may be recovered in the event 35 of the mechanism of the lock failing to work for some reason or the like the lower wall of the coin chute 7 adjacent to its lower end is provided with a gate or trap 19 capable of swinging downwardly to an open position 40 to establish communication between the chute 7 and an outlet chute 20. This gate 19 is connected through the medium of a link with a lever 21 fulcrumed between its ends and having the free end thereof connected 45 with a push rod 22, a coiled expansion spring 23 encircling the last-named rod and acting upon the same to hold the latter at its limit of outward movement and the gate in closed position. From this construction, it 50 will be seen that when the push rod 22 is moved inwardly against the action of the spring 23, the lever 21 will be swung about its fulcrum to open the gate 19 and so permit the coin on the contacts 8, 8 to gravitate 55 along the chute 20.

In Fig. 1 of the drawings, I have shown my improved lock as applied to a locker and in this instance the lock casing is set into a compartment formed in the door of the 60 locker, the outer wall of such compartment being formed with a slot 24 registering with the upper end of the coin chute 7 and with an opening 25 below the slot and establishing communication between the lower end 65 of the outlet chute 20 and a cup 26, such cup

being secured to the outer surface of the door and surrounding the opening 25 therein.

In Fig. 6 of the drawings, I have shown a modified construction of locking mechanism and in this form of my invention I pivotally secure to the inner end of the locking bolt 2 a lever 27 in lieu of the arm 4. This lever is fulcrumed between its ends as at 28 and has the upper end thereof pivotally connected as at 29 with the respective end of the rod 9 and equipped with an armature 30 disposed within the influence of the pole of the magnet 6. The lower end of this lever depends below the locking bolt 2 and has pivotally connected thereto one end of a retaining link 31 formed with a slot 32 parallel with its lower edge and having its rear end opening into a relatively short slot 33 arranged at right angles to the first slot. 80 These slots receive a pin 34 carried by the adjacent face of the locking bolt 2 and when the magnet 6 is energized the lever 27 swings about its fulcrum and so slides the locking bolt 2 to locking position. In the swinging 85 movement of the lever, the lower end thereof actuates the link 31 and slides the latter relatively to the bolt 2 so that the short slot 33 receives the pin 34. Thus, the locking bolt is held securely in locking position. The 90 link is placed in face to face contact with the lug 3 and when the key is inserted in the key hole to engage the lug and retract the bolt, the link is first contacted by the wing of the key and elevated to release the pin 34, 100 the wing subsequently engaging the lug to retract the bolt.

From the foregoing description taken in connection with the accompanying drawings, the construction, mode of operation and 105 manner of employing my invention will be readily apparent.

It will be seen that I have provided a lock wherein the bolt is coin controlled, electrically operated to locking position and key 110 operated to unlocking position and wherein the coin may be recovered by the user in the event of the locking mechanism failing to work.

While I have herein shown and described 115 one preferred form of my invention by way of illustration, I desire to have it understood that I do not limit or confine myself to the precise details of construction herein described and delineated, as modification 120 and variation may be made within the scope of the claims without departing from the spirit of the invention.

I claim:

1. In a lock, a locking bolt, electro responsive means for moving said bolt to locking position, a key for moving said bolt, means movable with said bolt to lock the key against removal when the bolt is inactive, a normally open electric circuit including said 125

electro responsive means and adapted to be bridged by a coin, and means movable with said bolt to move the coin out of circuit closing position.

5 2. In a lock, a bolt, an electro responsive device for moving said bolt to locking position, an electric circuit for said device, contacts in said circuit and adapted to be bridged to close the same, and means movable with said bolt to open the circuit at said contacts as the bolt moves to locking position, a key for retracting said bolt, and means movable rearwardly with said bolt to lock said key against removal.

15 3. In a coin controlled lock, a bolt, an electro responsive device for moving said bolt to locking position, an electric circuit for said electro responsive device, contacts in said circuit and adapted to be bridged by a coin to close the circuit, and means movable with said bolt to open the circuit at said contacts as the bolt moves to locking position.

25 4. In a coin controlled lock, a bolt, an electro responsive device for moving said bolt to locking position, an electric circuit for said electro responsive device, contacts in said circuit and adapted to be bridged by a coin to close the circuit, means movable with said bolt to open the circuit at said contacts as the bolt moves to locking position, and a key for retracting said bolt.

35 5. In a coin controlled lock, a bolt, an electro responsive device for moving said bolt to locking position, an electric circuit for said electro responsive device, contacts in said circuit and adapted to be bridged by a coin to close the circuit, means movable with said bolt to open the circuit at said contacts as the bolt moves to locking position, a key for retracting said bolt, and means movable rearwardly with said bolt to lock said key against removal.

45 6. In a coin controlled lock, a bolt, an electro responsive device for moving said bolt to locking position, an electric circuit for said electro responsive device, contacts in said circuit and adapted to be bridged by a coin to close the circuit, means for retracting said bolt, means whereby the coin may be recovered in the event of the lock failing to operate, and means movable with said bolt to open the circuit at said contacts as the bolt moves to locking position.

55 7. In a coin controlled lock, a bolt, an electro responsive device for moving said bolt to locking position, an electric circuit for said device, contacts in said circuit and adapted to be bridged by a coin to close the circuit, means whereby the coin may be recovered in the event of failure of operation of the lock, means movable with said bolt to open the circuit at said contacts as the bolt moves to locking position, and a key for retracting said bolt.

8. In a coin controlled lock, a bolt, an electro responsive device for moving said bolt to locking position, an electric circuit for said device, contacts in said circuit and adapted to be bridged by a coin to close the circuit, means whereby the coin may be recovered in the event of failure or operation of the lock, means movable with said bolt to open the circuit at said contacts as the bolt moves to locking position, a key for retracting said bolt, and means movable rearwardly with said bolt to lock said key against removal. 70 75

9. In a coin controlled lock, a bolt, an electro responsive device for moving said bolt to locking position, an electric circuit for said electro responsive device, contacts in said circuit and adapted to be bridged by a coin to close the circuit, and means movable with said bolt to disengage the coin from said contacts as the bolt moves to locking position. 80 85

10. In a coin controlled lock, a bolt, an electro responsive device for moving said bolt to locking position, an electric circuit for said electro responsive device, contacts in said circuit and adapted to be bridged by a coin to close the circuit, means movable with said bolt to disengage the coin from said contacts as the bolt moves to locking position, and means whereby said coin may be recovered in the event of failure of operation of the lock. 90 95

11. In a lock, a locking bolt, means for moving said bolt to locking position, a key for retracting said bolt, coin controlled means for energizing said first means, and means operable to render said coin controlled means inactive simultaneously with the movement of the bolt to locking position. 100 105

12. In a lock, a locking bolt, means for moving said bolt to locking position, a key for retracting said bolt, means for energizing said first means, and means operable from said bolt to render said last means inactive simultaneously with the movement of the bolt to locking position. 110

13. In a lock, a locking bolt, means for moving said bolt to locking position, a key for retracting said bolt, means operable from said bolt to lock said key against removal when the bolt is inactive, means for energizing said first means, and means operable from said bolt to render said last means inactive simultaneously with the movement of the bolt to locking position. 115 120

14. In a lock, a locking bolt, means for moving said bolt to locking position, a key for retracting said bolt, coin controlled means for energizing said first means, and means operable to render said coin controlled means inactive simultaneously with the movement of the bolt to locking position. 125 130

15. In a lock, a locking bolt, means for moving said bolt to locking position, a key for retracting said bolt, means operable from said bolt to lock said key against removal when the bolt is inactive, coin controlled means for energizing said first means, and means operable from said bolt to render said coin controlled means inac-

tive simultaneously with the movement of the bolt to locking position. 10

In testimony whereof I affix my signature in presence of two witnesses.

JOSEPH C. MOSLEY.
